UNITED STATES PATENT OFFICE.

JOHN A. PARKS AND GEORGE V. SHEFFIELD, OF NEW YORK, N. Y., AS
SIGNORS OF ONE-THIRD TO ERASTUS HAYES, OF SAME PLACE; SAID
SHEFFIELD ASSIGNOR TO SAID PARKS AND HAYES.

ELECTRICAL TYPE-WRITER.

SPECIFICATION forming part of Letters Patent No. 280,077, dated June 26, 1883.

Application filed July 15, 1882. (No model.)

To all whom it may concern:

Be it known that we, JOHN A. PARKS and GEORGE V. SHEFFIELD, both of the city, county, and State of New York, have invented 5 a new and useful Electrical Type-Writer; and we hereby declare the following to be a full and clear description thereof, which will enable those skilled in the art to make and use our machine.

10 Our invention relates to a machine for setting movable type and printing from the same, and also for delivering the type to a distributing-galley ready for redistribution to the font after they shall have been used to print from.

15 The nature of the invention consists in constructing a machine in which each particular letter or character used is placed upon a pair of ways or slides, between which the type are held by means of heads or projections formed on the tops of the types, so as to allow the types to slide along on and between the said ways, a spring-follower being arranged to push the type compactly up together and off of the opposite ends of the ways as rapidly as a toothed wheel which is arranged to engage the type at the delivery end of the said ways will permit. The said toothed wheel is operated by an electro-magnet, and the mechanism connected therewith is so arranged as to cause the movement off of the before-mentioned typeways of only one type at a time, which said delivered type will pass, type end down, through a delivery-tube, at the bottom end of which it will be set in a galley in proper form for printing any desired word or sentence, a number of the before-mentioned typeways and sets of type being provided, so as to have the machine contain all the letters and characters required to 20 print any required composition. From the forming-galley the types will slide onto a pair of printing-ways, where they will successively move between two sets of movable platens, by the operation of the first of which the type will be inked, and by the operation of the second the type will print the desired characters or words on a slip of paper passed between them. Both of the said sets of platens will be operated at the proper time by suitable electrical mechanism. After the type shall have 25 been printed from, they will be pushed off of

the ends of the printing-ways into a receiver we call a "distributing-galley," from which the type may be returned to their original places on the first-named ways or fonts. The 55 mechanism of this machine is such that it can be used for long-distance telegraphy or for office use as a simple type-writer.

The invention will be readily understood by reference to the drawings, of which—

60 Figure 1 is a longitudinal sectional elevation of the improved machine. Fig. 2 is a plan of the same. Fig. 3 is a detailed sectional elevation of one pair of the fontways, with the movable types carried thereon, the spring-fol- 65 lower for pressing the types close together on the ways, the type-mover connected therewith, the actuating-magnet, its armature, and re-tracting-spring. Fig. 4 is a plan of the parts shown in Fig. 3. Fig. 5 is a sectional detailed 70 elevation, showing the type-setting tube, the forming-galley, the printing-ways, the inking and printing platens and rollers, and the distributing-galley. Fig. 6 is a plan of the parts shown in Fig. 5. Fig. 7 is a transverse sec- 75 tion of the machine, taken on the line *x x* of Fig. 2. Fig. 8 is a transverse section of the machine, taken on the line *y y* of Fig. 5.

75 The type-mover consists of a ratcheted or serrated wheel, *A*, and a toothed wheel, *A'*, 80 both of which are secured to a common axle, *a*. These wheels will be of thin sheet metal—say one-twentieth of an inch to one-tenth of an inch in thickness—and they will be placed on the shaft *a* side by side, and either in contact 85 with each other or in close proximity. The axle *a*, as well as all other parts of this machine, will find bearings in the frame *Z*, which may be of any desirable form of construction.

85 A pawl, *B*, attached to the end of a pawl- 90 rod, *b*, is arranged to engage the ratchet-wheel *A*, and the said ratchet-wheel is moved by the said pawl, a proper reciprocating movement being imparted to the pawl by means of the electro-magnets *C*, armature *C'*, and retracting-spring *S*, to which armature one end of the pawl-rod is attached. To each of these type-movers *A A'* there will be attached a pair of sliding typeways, *D*, which act as a font for the sliding or movable type *d*. A spring-fol- 95 lower, *E*, is fulcrumed by its fixed end to some suitable part of the frame *Z*, or a suitable at-

tachment thereto, while the free end of the said follower is arranged to press against the types *d*, that are placed on the ways *D*, and press them up to and against the toothed wheel *A'*, so as to allow the said wheel to engage the said type, one at a time, and pull them off of the delivery ends of the ways *D*, and allow them to drop, type end downward, through the type setting or delivery tube *F*. As there are several of the fonts of type *d*—in fact, one for each of the letters or characters used—there are several branch tubes, *f*, all of which lead to the tube *F*, each of the said branch tubes *f* being placed so as to receive the type from a separate one of the mover-wheels *A'*, and the next branch pipe *f* to receive the type from the next mover-wheel *A'*, and so on through the whole series, the various types required to form any word or sentence to be sent through the branch pipes or conduits *f* and collected in the setting or delivery tube *F*, from the bottom end of which the types drop, type end down, upon the galley *G*, where the various types are collected and formed into the words, sentences, &c., which are required. The galley *G* will have a suitable lateral motion imparted to it automatically by the other mechanism of the machine, so as to provide for the placing of the type side by side as they are sent down through the delivery-tube *F*.

The mover-wheel *A'* has small teeth *a'* projecting radially from its periphery, the said teeth being so constructed and arranged as to catch and take the type *d*, one at a time, off of the ends of the ways *D* and drop them down through the tubes or chutes *f* *F*, as above explained. The top ends of the types *d* have small notches or recesses formed in their sides, just at the top ends of them, so as to permit the teeth *a'* to pass between the said types and pull them off their ways one at a time. In vertical section the top ends of the types *d* will be of a **T** shape, the projecting arms being formed for the purpose of affording holds or seats that are to rest on the ways *D*, while the body of the type hangs down between the said ways, as is clearly shown in Fig. 7. This arrangement permits the types being held face downward in and on the ways *D* and pushed along thereon, as above described. From the galley *G* the types *d* are pushed forward by suitable mechanism, so as to permit them to rest on the printing-ways *H*, the types still resting on their projecting heads, just as they did on the fontways *D*, and also on small ways *g*, which form the seats of the galley *G*. The ways *H* pass between upper and lower sets of movable platens, between the first pairs of which said platens the types are inked, and between the subsequent pairs of which said platens the impression of the type is printed on one or more slips of paper. In the drawings the first pair of these platens is represented by the flat platens *I* *J*, which are connected by means of the levers *i* and *j*, respectively, with the armature *K'* of the operating-magnet *K*, so that by the movement of the said armature *K'*,

by the well-known method of closing and opening an electrical circuit on the magnet *K*, the said upper and lower platens will be moved simultaneously up to and in contact with the types *d*—the upper platen to hold the type, and the platen *J* to press upward against and ink the faces of the type. In a similar manner the next pair of movable platens will be operated so as to press against the type for the purpose of printing therefrom. These second platens and their attachments are represented by the movable platens *L* and *M*, with their respective levers *l* and *m* and the actuating-magnet *N*.

The paper to be printed from is to be fed over the top of the printing-platen in a continuous slip, which feeding may be accomplished by any of the well-known devices for feeding slips of paper forward on telegraphic printing-instruments, and hence this mechanism need not be fully described.

As duplicate or triplicate printing instruments may be required, the ways *H* may be extended along beyond the printing-platens *L* *M*, and other similar printing-platens and their actuating mechanism added as may be desired. At the discharging end of the printing-ways *H* there is a distributing pair of ways or distributing-galley, *o*, which is to be combined with the said ways *H*, so that the types, after having been printed from, may be pushed off onto the said galley *o*, from which they may be redistributed to the first-named ways or font, *D*, for reuse in the machine.

Having described our invention, we claim—

1. The ratcheted type-mover *A* *A'*, the sliding pawl *B*, the actuating-magnets *C*, armature *C'*, and retracting-spring *S*', and spring-follower *E*, arranged and operated substantially as described.

2. The parallel typeways *D*, with their types *d*, the spring-follower *E*, the type-mover *A* *A'*, the pawl *B*, electro-magnet *C*, a suitable armature connected to and operating said pawl and type-mover, and a suitable retracting-spring, *S*', all combined substantially as described.

3. The type-galley *G*, in combination with the type-setting tube *F* and the printing-ways *H*, as and for the purpose set forth.

4. The movable platen *I* and the ink-platen *J*, in combination with each other and with the actuating mechanism and type-supporting ways *H*, substantially as described.

5. The combination of upper and lower pivoted vertically-moving platens, a pair of toggle-levers connected thereto and to a horizontally-moving armature, a suitable electro-magnet for operating the same, and ways or guides for carrying type between said platens, substantially as shown and described.

JOHN A. PARKS.
GEORGE V. SHEFFIELD.
